ABSTRACT: A motor operated ball mill is provided with opposed receptacles positioned over outlets so that the receptacles receive milled material, a grating being provided between the mill and the receptacle retaining the balls in the mill. A flap valve is provided for the receptacles to prevent the milled material from reentering the mill.

ATTORNEY

BALL MILL

The present invention relates to a ball mill particularly suitable for milling dry materials, in which means are provided retaining the balls within the mill while the milled material is allowed to pass to one or more receptacles from which it may be easily removed.

In prior ball mill operations both the grinding media or balls and the finely ground material were discharged into suitable containers and then separated by shaking or sieving the mixture through suitable grates. In other prior constructions the ball mills were built with permanent housings extending practically completely around the walls of the cylinders. The housings carried means for the ball mills to revolve, generally in the form of rings which were provided with suitable gasket materials for seals to prevent the leakage of the milled material outwardly of the housing. The milled material fell to the bottom of the housings and was thereafter removed as by shoveling into receiving containers. These constructions were disadvantageous in that in some cases the milled material stuck to the inside walls of the housings and to the outside walls of the ball mills which prevented complete recovery of the milled material. This was objectionable, not only because of the loss of the material, but also because of the possibility of contamination of another material thereafter placed in the mill.

The present invention aims to overcome the difficulties and disadvantages of prior ball mills by providing an improved ball mill which automatically separates the balls from the ground material retaining the balls within the mill and discharging the ground material.

In accordance with the invention this is accomplished by providing a ball mill in which the cylinder has its outlet in fluid communication with a receptacle, blocking means being provided between the cylinder and the receptacle so that the balls are retained in the mill. The receptacle is provided with an outlet for the rapid discharge of the accumulated ground material. Another feature is the provision of flow blocking means preventing the passage of the milled material back into the cylinder from the receptacle after it has been discharged therein.

The construction is advantageous in that it may be readily incorporated into existing ball mills with a minimum of conversion expense.

Other objects and advantages of the invention will be apparent from the following description and from the accompanying drawing which shows, by way of example, an embodiment of the invention.

In the drawing:

FIG. 1 is a schematic diagram showing a ball mill in accordance with the invention.

FIG. 2 is a side view of a grating used in the ball mill.

FIG. 3 is a plan view of the grating shown in FIG. 2.

FIG. 4 is a sectional view of a receptacle attached over the outlet of the ball mill in accordance with the invention.

Referring to the drawing there is shown in FIG. 1 a ball mill 10 including a pair of supporting frame members 11 and 12. The ball mill includes a cylinder 14 having ends 15 and 16. A plurality of mounting members 17 extend through the walls of the cylinder 14 and are used to attach longitudinally extending bars positioned on the inner surface of the cylinder 14 (not shown). Preferably a pair of receptacles 19 and 20 are attached to the cylinder 14, the receptacles being oppositely positioned so as to balance the assembly. The receptacles 19 and 20 are identical. At end 16 of the ball mill 10 is a ring gear 21 engaged by a pinion 22 rotated by a motor 24 through a gear reduction box 25. The motor and gear box assembly may be carried on a shelf 26 of the frame 12.

Positioned between the receptacles 19 and 20 and the cylinder 14 are the gratings 30 each having a pair of mounting lugs 31 and 32 and a generally rectangularly shaped frame 34. Spaced somewhat away from the frame 34 is an inner frame 35 carrying a plurality of rods 36, the spacing between the rods 36 and between the frames 34 and 35 being less than the diameter of the balls used so that the grating 30 effectively

separates the milled material from the balls. The upper frame 35 is attached to the lower frame 34 by members 37 and 39. The grating member 30 is positioned in the outlet of the cylinder 14 with the upper frame 35 facing the interior of the cylinder. The receptacles 19 and 20 are secured in position over the grating holding it in position.

A sectional view of the receptacle 19 is shown in FIG. 4. A tubular member 40 is provided with a flanged end 41 adapted to be secured over the grating 30 about the outlet of the cylinder 14, suitable apertures 42 being provided for the passage of retaining bolts. The tubular member 40 extends through an opening in the sidewall 43 of the receptacle 19, the sidewall 43 being preferably of generally cylindrical shape.

The receptacle 19 may be secured in position with the tubular member 40 by welding 44 or other suitable means. The inner end of the tubular member 40 is made at an angle providing a short side 45 and a longer side 46. A flap valve 48 is pivotably attached to the short side 45 by a hinge 49. The cylindrical wall 43 is closed by an end wall 50 at one end thereof while the other end is provided with a throat 51 having an outlet opening 52 at its outer end. About the outlet opening 52 is positioned a ring 54 apertured to receive a swing bolt 55 and at its opposite end fitted with a shoulder bolt 56. A disc-like closure member 57 is pivoted in the swing bolt 55 and notched so as to be releasably secured by the shoulder bolt 56.

Referring to FIG. 1 it will be noted that two receptacles 19 and 20 are positioned on opposite sides of the cylinder 14 after the ball milling cycle has been completed, the ball mill having been rotated with solid closures in place blocking the openings adapted to receive the receptacles 19 and 20 until the desired fineness of the milled material is achieved. Obviously a single receptacle might be used if suitable counterbalance means is provided.

The cylinder 14 may be about half filled with balls or with balls and material being milled. As the cylinder rotates the finer of the milled material passes through the grating 30 into the tubular member 40 from where it drops into the receptacle 19 when the flap valve 48 opens. As the cylinder 14 continues to rotate the flap valve is closed by gravity retaining the finely milled material in the receptacle 19. The milling operation may be stopped and the machine turned so that one of the receptacles 19 is positioned at the lower end thereof whereupon the shoulder bolt 56 may be loosened and the disc closure member 57 swung away allowing the milled material to be removed.

It will be noted that the flap valve 48 will be open so as to receive material from the ball mill during about one half of each revolution and closed during the remaining half of the revolution so as to prevent the material from falling back into the ball mill.

While the invention has been described and illustrated with reference to a specific embodiment thereof, it will be understood that other embodiments may be resorted to without departing from the invention. Therefore, the form of the invention set out above should be considered as illustrative and not as limiting the scope of the following claims.

I claim:

1. A ball mill comprising a rotatable cylinder, means to rotate the cylinder, outlet means for the cylinder, a plurality of balls within the cylinder, means blocking the passage of balls outwardly through said outlet but allowing the passage of material below a predetermined blocking a receptacle secured to said cylinder about said outlet, flow blocking means preventing flow of material back from said receptacle to said cylinder, and discharge outlet means for the said receptacle.

2. A ball mill according to claim 1 in which a pair of receptacles are provided oppositely positioned on said cylinder.

3. A ball mill according to claim 1 in which said means blocking the passage of balls outwardly through said outlet but allowing the passage of material below a predetermined size is a grating including a plurality of rods spaced a predetermined distance.

4. A ball mill according to claim 1 in which said receptacle is of cylindrical shape having its axis positioned tangentially to the periphery of said cylinder.

5. A ball mill according to claim 4 in which an outlet is positioned at one end of said receptacle.

6. A ball mill according to claim 5 in which a plate is swingably mounted in closing relationship with the outlet of said receptacle.

7. A ball mill according to claim 1 in which said flow blocking means is a gravity actuated flap valve positioned at the inlet to said receptacle such that it falls open to receive material during a portion of the revolution of the cylinder and falls closed during the remainder of the revolution of the cylinder so that material does not pass back from the receptacle to the cylinder.

8. A ball mill according to claim 7 in which a flanged tube is provided between said receptacle and said cylinder, the flanged end of the tube attached to said cylinder about the cylinder outlet, the other end of said tube extending within said receptacle, said flap valve pivotably mounted on said

other end of said tube.

9. A ball mill according to claim 3 in which said receptacle is of cylindrical shape having its axis positioned tangentially to the periphery of said cylinder, outlet means positioned at one end of said receptacle, a plate swingably mounted in closing relationship with the outlet of said receptacle, said flow blocking means being a gravity actuated flap valve positioned at the inlet to said receptacle so that it falls open to receive material during a portion of the revolution of the cylinder and falls closed during the remainder of the revolution of the cylinder in order that material does not pass back from the receptacle to the cylinder, and a flange tube is provided between said receptacle and said cylinder, the flanged end of the tube attached to said cylinder about the cylinder outlet, 15 the other end of said tube extending within said receptacle, said flap valve being pivotably mounted on said other end of said tube.

10. A ball mill according to claim 9 in which a pair receptacles are provided oppositely positioned on said cylinder.

UNITED STATES PATENT OFFICE
CERTIFICATE OF CORRECTION

Patent No. 3 549 094

Dated December 22, 1970

Inventor(s) Jacob Kurtz

It is certified that error appears in the above-identified patent and that said Letters Patent are hereby corrected as shown below:

Column 1, line 40, change "discharge" to
--discharged--.

Column 1, line 59, remove the word "and"
after "17".

Column 2, Claim 1, line 65, after "pre-
determined" remove the word "blocking" and insert the
word --size,--.

Column 4, Claim 10, line 18, after "pair"
insert the word --of--.

Signed and sealed this 23rd day of March 1971.
